DRAWER GUIDE AND SUPPORT

Chester C. Lucas, Rockford, Ill., assignor to Geo. D. Roper Corporation, Rockford, Ill., a corporation of Illinois

Application June 29, 1940, Serial No. 343,114

4 Claims. (Cl. 45—77)

This invention relates to drawer guides and supports embodying anti-friction ball bearings.

The principal object of my invention is to provide a drawer guide assembly of simple, economical and durable construction that combines noise dampening and anti-friction qualities and which is designed to be readily installed in a cabinet compartment.

A further object of my invention is to provide a drawer guide assembly of a semi-rigid and resilient construction that will withstand stresses to which the drawer may be subjected in the open positions, without permanently distorting the opposed guide rails and resulting in binding and irregular drawer movement. The guide rails of my invention are specially formed to obtain the desired strength and rigidity without sacrificing lightness.

Another important object of my invention is to provide a drawer guide assembly which can be accurately fabricated in quantity production so that the drawer will move with uniform smoothness throughout its travel. This object is achieved in my invention through the use of V-shaped rails disposed in laterally spaced relation and balls reliably engaged therebetween, the said balls being held therebetween under compression resulting from a slight springing apart of said rails, whereby to eliminate play and make for quiet operation.

The invention is illustrated in the accompanying drawings, in which—

Figure 1 is a perspective view of a kitchen range showing as prominently as possible a drawer and cooperating guide and support assembly made in accordance with my invention;

Fig. 2 is a top view of the movable drawer frame and the stationary frame;

Fig. 3 is a longitudinal vertical section of the drawer and drawer guide and support assembly, showing the drawer in an open position;

Fig. 4 is a top view of one side portion of the drawer guide and support assembly showing the movable drawer frame in the open position of Fig. 3;

Fig. 5 is a transverse vertical section of the drawer and drawer guide and support assembly on a larger scale;

Fig. 6 is a vertical longitudinal sectional detail of one of the clips that are used in attaching the drawer to the movable frame;

Fig. 7 is a vertical longitudinal sectional detail of the spring pressed door cushioning and retaining roller, and

Figs. 8, 9, and 10 are fragmentary sectional details showing modified or alternative constructions of the door guide rails.

The same reference numerals are applied to 5 corresponding parts throughout the views.

A stationary frame consisting of two sheet metal side rails 8 and 9 in parallel relation and four cross-members 10 is horizontally positioned within a casing formed in the present instance by a compartment of a kitchen range, generally designated by the numeral 11, which has been designed for the reception of a drawer. The cross-members 10, which are downwardly facing channels, are spaced along the rails 8 and 9 and disposed at right angles thereto and are welded or otherwise rigidly secured to the bottom faces of the base flanges 12 and 13 on the rails. The rails, 8, 9, are formed to provide inwardly facing V-shaped grooves or ball-ways *a*, extending substantially their entire length, and along the tops of the rails and integral therewith extend reinforcing flanges 14, 15, respectively.

The movable frame, which is suitably designed for the mounting of a drawer 16, consists of parallel sheet metal side rails 17, 18, that are connected by four cross-members 19. The cross-members 19, which are upwardly facing channels are welded or otherwise rigidly secured at their respective ends to the top faces of base flanges 20 and 21 of these movable rails. The rails 17, 18, are formed to provide outwardly facing V-shaped grooves or ball-ways *b* and integral reinforcing flanges 22, 23, respectively, both of which extend for substantially the length of the rails.

The movable frame is positioned within the stationary frame, as illustrated in Fig. 5, so that the movable side rails and stationary side rails are in parallel spaced relation, two pairs of balls 24, 25, and 26, 27, being rollably engaged therebetween in the grooves *a* and *b*. The balls of both pairs are normally spaced lengthwise of the rails, as shown in Fig. 2. The grooves *a* and *b* have their sides in substantially right angle relationship, and the balls 24—27 are of such size as to engage in the grooves and roll on substantially horizontal axes that substantially bisect the angles defined by said grooves. When the balls 24—27 are maintained in properly spaced relation within the rails, they provide an anti-friction and non-tiltable mounting for the movable frame on which the drawer 16 is mounted. Stop lugs, which are screws entered in threaded and properly spaced holes in the rails, are provided at 28, 29 on the stationary rails and at 30, 31 on the

movable rails. As the movable frame moves outwardly relative to the stationary one, the anti-friction balls will travel a distance along the stationary rails that is a fraction of the distance moved by the movable frame. The lugs 28 on the stationary frame and the lugs 33 on the movable frame are so spaced to allow only the desired amount of drawer opening movement. When the forward balls 24 are stopped by the lugs 28, the lugs 30 will engage the same balls from behind, thereby preventing any further movement of the movable frame. Likewise lugs 29 on the stationary frame and lugs 31 on the movable frame are so spaced that the balls 25 will meet the stop lugs 29 and will be engaged by lugs 31 from behind when the front balls reach their limits of forward travel. As the movable frame is returned, all of the balls will roll back to approximately their starting positions, but in the event one or more fail to roll the full distance back, such balls will be automatically jogged back into correct relationship to the other balls by the lugs 28-31 the next time the drawer is pulled all of the way out, as should be clear from a study of Fig. 4.

Prior practice has indicated that it is only with V-shaped rails, in which each rollably engaged ball travels in identical tracks in the grooves of the rails, that a constant distance of travel of the ball on the rails can be maintained. This characteristic of the laterally spaced rails, having substantially 90° V-grooves, and the rollably engaged balls therebetween is highly important in achieving the desired operation of the present drawer guide mechanism. If the distance of travel of different balls varied, the predetermined maximum opening of the drawer could be obtained in certain cases only by skidding some of the balls certain distances to the forward stop positions by engagement therewith from behind by their related lugs mounted on the movable frame. Such a skidding movement obviously would produce a binding effect and would sooner or later cause enough wear on the balls to ruin the smooth rolling action entirely. The novel construction and operation of the present guide eliminate those objections found in other guides.

The stationary and movable side rails are spaced so that the balls engaged between them are actually held therebetween under a certain amount of pressure, that is to say the balls act to spread apart the two rails on each side of the drawer. This compression mounting of the balls that is made possible through the semi-rigid construction of the rails has a noise dampening effect, irrespective of whether the mounted drawer is filled or empty, that is not possible to achieve with other ball and rail assemblies with which I am familiar. Such a dampening effect is especially desirable where the drawer and enclosing casing are of sheet metal construction, for in this type of cabinet the slightest sound tends to be amplified. The compression mounting of the balls also provides sufficient drag to prevent too rapid opening or closing of the drawer and the resulting slams which might occur, inadvertently, where the balls are freely mounted. This drag is also sufficient to maintain the drawer easily in any partly opened position.

The resilient quality of the opposed pairs of rails made possible through their semi-rigid construction and their mounting on the respective cross-members gives a certain amount of flexibility to the mounting of the movable frame within the stationary frame so that when ex-

treme upward or downward stress is applied to the drawer in the open positions, the opposed rails will flex apart at the top or bottom, though not sufficiently to release the balls retained therebetween, and, upon release of the stress, will return to the normal spaced relationship. It has been found that a more rigid rail construction and mounting than one substantially as described is disposed to reset itself at the stress position and thereby result in misalignment of the opposed rails and, consequently, binding and irregular operation, which are faults not present in this construction.

The drawer 16 comprising front and back walls 32 and 33, two side walls 34, and a recessed bottom 35 is secured to the back of the movable frame by two clips 36 and 37, and to the front portion by two screws 38 and 39, which pass freely through holes in the bottom of the drawer 20 and into registering threaded holes 40 and 41 in the front cross-member 19 of the movable frame. The clips 36 and 37 are suitably secured to the top face of the rear cross-member 19 of the movable frame and, as shown in Fig. 6, have 25 end portions 42 adapted to be entered in slots 43 in the back wall 33 of the drawer. It will be obvious that through the described clip and screw means the drawer 16 may be very readily attached or detached from the movable frame.

A roller 44 is rotatably mounted on the rear end of a rearwardly extending U-shaped wire spring 45 that is secured by a screw 46 on rear cross-member 10 of the stationary frame between struck-up bosses 47. The spring 45 is upwardly inclined so that when the rear cross-member 19 of the movable frame travels past the roller 44 the upwardly indented portion 48 of the rear cross-member receives the roller, as illustrated in Fig. 7. This roller detent device acts to cushion the drawer in closing, thereby preventing banging, and also to retain the drawer in the closed position so as to prevent any inadvertent opening through rebound or drifting.

The side rails 8 and 9 of the stationary frame 45 have their flanges 12 and 13 extended at the rear ends of these rails, as indicated at 49, and entered through slots 50 provided in the back wall 51 of the range 11 for support of the rear end of the stationary frame in a way which enables quick and easy assembling of the drawer structure in the range. At the front end of the stationary frame are some sheet metal brackets 52 fastened to the front ends of the side rails 8 and 9 by screws 53 entered through the flanges 12 and 13, 55 these brackets being secured to the front frame 54 of the range by screws 55, thus further facilitating assembling of the drawer structure in the range.

In Fig. 6 I have shown a different construction for the side rails of the stationary and movable frames, only one side rail 8a of the stationary frame and one side rail 17a of the movable frame being shown, and it being understood that the other side of the drawer guide structure is a counterpart of what is illustrated. The side rail 8a, it will be noticed, has a brace strip 56 extending lengthwise of the rail in a plane at approximately 45° to the horizontal with its upper edge fitting in the crotch formed between the reinforcing flange 14 along the top and the adjacent side wall of the V-groove a, while the lower edge of the strip is welded as at 57 to the top of the bottom flange 12. The side rail 17a of the movable frame is likewise equipped with a bracing strip 58 having abutment along its upper edge in

the crotch under the top flange 22 of the rail while the lower edge is welded, as at 59, to the top of the bottom flange 20 of said rail. These strips 56 and 58 serve to buttress the V-grooved portions of the rails 8a and 17a so that there will be only a small fraction of the amount of "give" in these portions of the rails that there is when the rails are without such bracing, as in Fig. 5 for example. Two other alternative constructions are illustrated in Figs. 9 and 10, Fig. 9 showing only the side rails of the stationary frame, like that shown at 8a, braced as indicated at 56, whereas Fig. 10 shows the side rails of the movable frame, like that indicated at 17a, braced as shown at 58. With these two alternative constructions, it is clear that the side rails of whichever frame is without bracing means will absorb nearly all of the give.

It is believed the foregoing description conveys a good understanding of the objects and advantages of my invention. The appended claims have been drawn to cover all legitimate modifications and adaptations.

I claim:

1. A drawer guide construction comprising in combination, a stationary frame and a movable frame, one of said frames comprising parallel sheet metal side rails for opposite sides of a drawer rigidly interconnected and spaced apart by a plurality of cross-members, each side rail providing a single, substantially vertical, relatively resilient portion bent to V-shaped section to form an inwardly facing ball-way, the other of said frames comprising parallel sheet metal side rails for opposite sides of the drawer rigidly interconnected and spaced apart by a plurality of cross-members, each of the latter side rails providing a single, relatively resilient, vertical portion bent to V-shaped section to form an outwardly facing ball-way, a drawer having means for securing the same to said movable frame, the side rails of one of said frames being spaced so as to operate between the side rails of the other of said frames in closely spaced relation thereto and with companion ball-ways in register, and bearing balls disposed between the side rails of the frames having close rolling fits in said ball-ways, said balls being of sufficiently enlarged diameter in relation to the size of the ball-ways and the spaces therebetween to spread the side rails of each pair apart when the balls are entered therebetween, whereby the balls are held between the rails under a predetermined pressure, substantially as and for the purpose described.

2. A drawer guide construction comprising, in combination, a stationary frame and a movable frame, one of said frames comprising parallel sheet metal side rails for opposite sides of a drawer rigidly interconnected and spaced apart by a plurality of cross-members, each side rail providing a single, substantially vertical, relatively resilient portion bent to a V-shaped section to form an inwardly facing ball-way, the other of said frames comprising parallel sheet metal side rails for opposite sides of the drawer rigidly interconnected and spaced apart by a plurality of cross-members, each of the latter side rails providing a single, relatively resilient, vertical portion bent to V-shaped section to form an outwardly facing ball-way, a drawer having means for securing the same to said movable frame, the side rails of one of said frames being

spaced so as to operate between the side rails of the other of said frames in closely spaced relation thereto and with companion ball-ways in register, and bearing balls disposed between the side rails of the frames having close rolling fits in said ball-ways.

3. A drawer guide structure comprising a pair of resilient sheet metal rails formed to provide inwardly facing V-shaped grooves, means for mounting said rails in parallel relation along the side walls of a drawer casing, other resilient sheet metal rails formed to provide outwardly facing V-shaped grooves and disposed in parallel spaced relation with respect to the stationary rails and with the outwardly facing grooves registering with the inwardly facing grooves, a drawer adapted to operate within the said casing and secured to the movable rails for movement therewith, balls rollably engaged within the grooves of and between the respective movable and stationary rails, the said balls being held therebetween under compression resulting from a slight springing apart of the resilient guide rails, each of the rails of one set having laterally projecting substantially parallel top and bottom flanges extending in posterior relation to the V-formed ball receiving grooves, one of the flanges on each rail being an attaching flange and the other a reinforcing flange, and means for bracing said set of guide rails to reduce lateral give thereof away from the other guide rails, comprising brace strips, one for each of said rails, disposed in acute angular relation to the attaching flanges resting against the backs of the V-formed portions of said rails and having the one longitudinal edge portion of the strips in abutment with the reinforcing flanges and the other longitudinal edge portion of the strips secured to the attaching flanges.

4. A drawer guide structure comprising a pair of resilient sheet metal rails formed to provide inwardly facing V-shaped grooves, means for mounting said rails in parallel relation along the side walls of a drawer casing, other resilient sheet metal rails formed to provide outwardly facing V-shaped grooves and disposed in parallel spaced relation with respect to the stationary rails and with the outwardly facing grooves registering with the inwardly facing grooves, a drawer adapted to operate within the said casing and secured to the movable rails for movement therewith, balls rollably engaged within the grooves of and between the respective movable and stationary rails, the said balls being held therebetween under compression resulting from a slight springing apart of the resilient guide rails, each of the rails of the two sets having laterally projecting substantially parallel top and bottom flanges extending in posterior relation to the V-formed ball receiving grooves, one of the flanges on each rail being an attaching flange and the other a reinforcing flange, and means for bracing the two sets of guide rails to reduce lateral give thereof away from one another, comprising brace strips, one for each of said rails, disposed in acute angular relation to the attaching flanges resting against the backs of the V-formed portions of said rails and having the one longitudinal edge portion of the strips in abutment with the reinforcing flanges and the other longitudinal edge portion of the strips secured to the attaching flanges.

CHESTER C. LUCAS.
